[57] CLAIM

The ornamental design for a two handle roller, as shown and described.

DESCRIPTION

FIG. 1 is a top plan view of a two handle roller showing my new design;

FIG. 2 is a side elevational view thereof;

FIG. 3 is a bottom plan view thereof;

FIG. 4 is an end elevational view of the roller from the left of FIG. 2; and

FIG. 5 is an end elevational view of the roller from the right of FIG. 2.
